CHARLES W. GRAHAM, OF ROME, NEW YORK, ASSIGNOR, BY MESNE ASSIGNMENTS,
TO AMERICAN CAN COMPANY, OF NEW YORK, N. Y., A CORPORATION OF NEW
JERSEY.

CAN-HEADING MACHINE.

969,470.

Specification of Letters Patent.

Patented Sept. 6, 1910.

Application filed April 10, 1905. Serial No. 254,778.

To all whom it may concern:

Be it known that I, CHARLES W. GRAHAM, residing at Rome, in the county of Oneida and State of New York, have invented certain new and useful Improvements in Can-Heading Machines, of which the following is a full, clear, and exact description, such as will enable others skilled in the art to which it appertains to make and use the same.

This invention relates to machinery for forming cans and the like.

One of the objects thereof is to provide a simple and efficient machine of the above general type adapted to place heads on can bodies.

Another object is to produce a machine of the above nature, several of the elements of which are readily adjustable with relation one to another.

Another object is to provide a machine of the above type having a capacity for performing its functions at a high rate of speed and having a maximum output in cans per hour.

Another object is to provide means in a can heading machine for rigidly pressing the heads into position and holding the same in such condition under a reduced pressure.

Another object is to provide means adapted positively to remove or strip the headed cans from the parts within which they rest.

Other objects will be in part obvious and in part pointed out hereinafter.

The invention accordingly consists in the features of construction, combinations of elements, and arrangement of parts which will be exemplified in the machine herein-after described, and the scope of the application of which will be indicated in the following claims.

In the accompanying drawings, wherein is shown one of various possible embodiments of my invention: Figure 1 is a side elevation of the same. Fig. 2 is an enlarged detail section taken on the line $x-x$ of Fig. 1. Fig. 3 is an enlarged plan of a portion of the supply chute. Fig. 4 is a side elevation of the upper portion of this embodiment of my invention showing the supply chute in its alternative positions with respect to Fig. 1. Fig. 5 is a front elevation of the central portion of the machine. Fig. 6 is a sectional elevation taken on line $y-y$ of Fig. 5. Fig. 7 is an enlarged detail sec-

tional view taken on line $z-z$ of Fig. 6. Fig. 8 is an elevation similar to Fig. 5, certain parts being removed in order to show the construction more clearly. Fig. 9 is an enlarged detail view of a sliding jaw and parts associated therewith.

Similar reference characters refer to similar parts throughout the several views.

As tending to cast light upon the general nature of certain features of my invention, it may here be noted that it is proposed to avoid uncertainty in action by providing rigid means for removing or stripping the headed can bodies from the parts in which they rest, injury to the cans being prevented by holding the same flexibly at the time at which the stripping takes place, thus guiding the cans and preventing rattling or displacement thereof. As these flexible holding means might be unsuitable efficiently to head the cans, separate unyielding means are provided for forcing the heads into position, subsequent to the action of which the above-mentioned flexible holding means are automatically brought into play. It is also proposed to increase the output of the machine by the provision of can-holding means so disposed as to permit the can-receiving means to lie closely together, thus increasing the rate of production with a given peripheral speed, as will be pointed out more in detail hereinafter. The above are among the preferred constructions wherein the means of attaining certain objects of my invention are embodied.

Referring now to the embodiment shown in the accompanying drawings, there is shown in Fig. 1 a bed or base 1 provided with uprights or standards 2, these standards being positioned at each end of the machine, as is more clearly indicated in Fig. 5 of the drawings. Projecting upwardly from each standard 2 and preferably formed integral therewith is a rigid arm 3, these arms being connected at their upper ends 95 as by a cross bar 4. Pivotedly mounted upon this cross bar as by the straps 5 terminating in sleeves 6 is a chute 7 comprising broadly two portions 8 and 9 inclined with respect one to another. The upper 100 portions 8 of the chute comprise side channels 10 adapted to receive and guide the separate heads or end pieces for forming can bodies, and between the inner walls 11 of these guiding channels is a third channel 110

12 of considerably greater width adapted to guide the bodies of the cans. The floor of this last-mentioned guiding channel comprises a pair of strips 13 supported and held in properly spaced relation to the channels 10 by means of the threaded tie rods 14 and sleeves 15 fitted thereon. Similar tie rods 16 connect the upper portion of the chute adjacent the bend thereof and straps 17 are bolted or tied to the inner walls of the guiding channels 10 along the depending portion 9 of the chute. Also positioned along the portion 9 are the guiding bars 18 which are bolted in the position shown in Fig. 5 of the drawings, and prevent a displacement of the can bodies in a forward direction. The lateral straying of the heads of the cans is prevented by rigid guides 19 bolted to the straps 5 and having at their lower ends plates 20 for the purpose of properly guiding the can heads into the machine. Displacement of the bodies in a forward or upward direction at and above the bend of the chute is prevented by a flat guide 21 bolted between the bars 18 as at 22 and curving upward and rearwardly over the chute. Bolted upon the lower portion of the chute at 23 and 24 are a pair of straps 25 similar to the straps 5 provided at their forward ends with forks 26 adapted to engage a cross bar 27 adjustably mounted within the arms 3 before described.

Upon each of the guides 19 is pivotally mounted an L-shaped lever 28, which is held in either one of the two alternative positions by reason of the engagement of a flat spring 29 fixed upon the guides either with the squared end or the side of the lever. These levers are so shaped and positioned as when swung into their inward position, shown in Fig. 2 of the drawings, to obstruct the passage both for the heads and bodies of the cans. In this manner, if it be desired to lock the cans in the chute for any reason, the same is readily accomplished merely by swinging the levers 28 into their innermost position, whereas, in their normal position they permit a free passage for these parts, and as above mentioned, spring 29 is adapted to hold these levers in either their inner or their outer positions. The entire chute is thus pivotally mounted by means of the heavy straps 5 upon the cross bar 4 and may, if desired, be swung into the position indicated in Fig. 4 of the drawings, in which ready access to the machine is permitted and the feeding of the can heads and bodies stopped. When swung downwardly into its normal position, however, as shown in Fig. 1, the forked straps 25 engaging the cross bar 27 limit the movement of the chute in this direction and the chute may be locked in this position, in any desired manner. The function of the L-shaped levers above-described should become more clearly ap-

parent in this connection, inasmuch as, were it not for these parts, when the chute is swung into a position shown in Fig. 4, the can heads and bodies remaining therein would be discharged therefrom.

Referring now to Fig. 1 of the drawings, there is shown journaled within the standards 2 a shaft 30 having fixed upon one end a spur gear 31 intermeshing with a pinion 32 journaled upon a stud 33 preferably formed upon the frame of the machine. In fixed relation to pinion 32 and preferably formed integral therewith, is a pulley 34 driven by belt 35 from any desired source of power.

Mounted upon the shaft 30 are a pair of what may be termed "disks" 36, of which, as the two are identical, one only will be described. Disk 36 is provided with an extended sleeve-like hub, 37 split as indicated at 38, and adapted adjustably to be clamped to the shaft as by bolts 39. Formed within the disk is an opening 40 provided with an extended bearing 41 for a rod 42 passing through a similar opening in the remaining disk. It will thus be seen that these disks are adjustable longitudinally and rotatably with respect to the shaft and yet are maintained in their desired angular relation by the rod 42.

Mounted above the circumference of the disks 36 are a series of can receiving members or "cradles" 43 each of these parts being provided with a depending flange 44 bolted to the disk. These members are provided with recesses or grooves 45 within which the head is to rest, formed of such depth as to properly space the edges of the head with reference to the edges of the body. It may here be noted that suitable slots 46 are provided so as to permit the passage of the guiding plates 20 above referred to, thus securely guiding the heads into their proper position within the receiving cradles. As these can receiving members with the parts associated therewith are substantially identical, one only will be described. The outer portion of the member 43 is of a hollow cylindrical form and has fixed therein an annular abutment 47. Positioned within this abutment is a guide rod 48 having a head or piston 49 adapted to rest against the inner walls of the abutment and thus limit the outward movement of the rod. The outer end of rod 48 is preferably rounded as shown at 50 for a purpose hereinafter described. Secured upon rod 48 as by a pin 51 passing through the slot 52 is a collar 53 fitting the inner surface of the outer cylindrical portion of the member 43 and adapted to slide therein. A heavy spring 54 coiled about the rod and taking against the abutment 47 and collar 53 normally holds the head 49 in its outermost position shown in Fig. 7 of the drawings. Within a chamber

55 formed in the rod 48 and having its outer end closed by means of a plug 56 positioned therein, is a coiled spring 57 which tends to force a plunger 58 slidably mounted therein against the pin 51. In this manner it will be seen that any pressure applied to the rounded end 50 of the rod 48 will force the same inwardly by direct pressure, whereas, a pressure in the same direction 10 upon the collar 53 will act only through the spring 57 until this member is compressed so as to permit the pin 51 to strike the inner end of the slot 52. This action will be described more at length hereinafter.

15 Mounted about the cylindrical portion of the member 43 is a sleeve or slide 59 which is prevented from rotating thereon as by means of the pin 60 adjustably held in flange 44 by screw 61 and reciprocating 20 within a passage 62 formed in the lower part of the sleeve. Upon the upper side of sleeve 59 as shown in Fig. 7 of the drawings, is a boss 63 having held thereon by means of screw 64 an anti-friction roller 65. The 25 inner side of the sleeve is shaped so as to form ways or guides 66 within which is slidably mounted a clamping member or jaw 67 which normally rests upon the outer portion of the member 43. It may here be 30 noted that terms of the nature of "inwardly" and "outwardly" are used with reference to the center of the machine as the innermost point. Tied to the upper end of the jaw 67 as by means of a screw 68 the 35 movement of which is limited by shoulder 69 is an anti-friction roller 70, the function of which will be hereinafter described.

As shown in Fig. 6 of the drawings, a 40 number of the above described receiving members, with the parts associated therewith, are positioned about the disks 36, the same facing inwardly toward one another, as shown in Fig. 5 and being spaced apart for a purpose hereinafter described. Also, 45 each cradle or can receiving member 43 is provided with two lips 71 extending laterally toward the next adjacent cradle upon each side thereof for the purpose of bridging over the gap between these parts and 50 preventing jarring or injury to the cans which might otherwise result.

Connected with the cross bar 27 as by 55 means of the brackets 72 are a pair of guides 73 adapted to coact with the rollers 65 as shown in Fig. 5 of the drawings. These guides are laterally adjustable upon the bar 27 and are secured to the standards 2 at their lower end by means of threaded rods 74 and nuts 75. As these guides with the 60 parts associated therewith are identical, one only will be described in detail. Guide 73 which is, in general, of the cross-section of "channel iron" with the flanges turned inwardly, comprises portions 76 and 77 lying 65 within a plane taken through the rollers 65

with the sleeves 59 in their retracted positions. Intermediate these portions and connected therewith, as by the curved or inclined portions 78 and 79, is a central portion 80 lying within the plane of the rollers 65 when at the innermost limit of their path of travel. It will thus be seen that as the sleeves 59 rotate with the shaft 30 the rollers 65 pass at each revolution into the portions 76 of the guides and are moved by the curved or inclined portions 78 inwardly so as to bring the sliding jaw 67 above the can body resting within the cradle 43. This position of the sleeve is maintained for a portion of the revolution of the shaft and the slides 80 are finally retracted by the curved portions 79 of the guides. This cycle of operations is repeated with each revolution of the shaft.

Mounted upon guides 73 is a bracket 81 having pivotally mounted thereon the guide 82. This guiding member is adjustable with reference to guide 73, as by means of bolt 83, within a curved slot 84 in a bracket 85 hereinafter referred to. It will thus be seen that by means of loosening the bolt 83, the 90 guide 82 may be swung about its pivotal connection with the bracket 81 and secured in any desired position. Formed upon guide 82 are flanges 86 and 87 respectively adapted to coact with the opposite sides of 95 the rollers 70, thus alternately depressing and raising each sliding jaw 67 according as the corresponding roller engages one or the other of these flanges. It will be noted by reference to Fig. 5 of the drawings that the 100 central portion of the guide 82 is free from guiding flanges, thus leaving the jaws without positive control from the guides at this point.

Mounted upon the standards 2 by means 105 of rigid arms 88 is a heavy cross bar 89 upon which is mounted a cylinder 91 having fixed at its upper end a collar 92 within which a guiding rod 93 fixed to a piston 94 is adapted to slide. A heavy spiral spring 110 95 is preferably compressed between the piston 94 and the fixed collar 92 tending normally to hold the former in its outermost position with reference to the cylinder.

Rotatably mounted upon the cross bar 89 115 as by means of sleeve 96, is a lever 97 abutting, through the set screw 98 held in position by the lock nut 99, against the face of the piston 94. The lower end of this lever is bifurcated and within the arms 100 thereof is journaled a roller 101. The downward movement of the lever is limited by means of a set screw 102 mounted within a lug 103 in fixed relation to cylinder 91 and projecting between the arms 100 of the lever 125 and engaging a lug 104 formed thereupon. In this manner the compressed spring 95 tends by means of the set screw 98 to rock the lever 97 about the cross bar and thus force the roller 101 toward the center of the 130

machine, such movement being adjustably limited by means of the set screw 102 as above indicated. Roller 101 is so positioned as to be directly over the upper or outer 5 ends of the slidable jaws 67 when the same are forced into their inner position by means of the guide 82, these ends being curved about the shaft as a center. In this manner as the jaws are released by the 10 flanges 86 upon guides 82 they are subjected to a readily adjustable elastic pressure transmitted thereto through the rollers 101, thus holding the same firmly in their depressed position while the can is acted upon as hereinafter described.

The means for actuating the rods or plungers 48 in the desired manner preferably comprise the following parts. As these means are identical upon both sides of the 20 machine, that upon one side only will be described. Journaled within a cross bar 105 connecting the rods 106 and 107, which are adjustably positioned upon the standards of the machine by means of nuts 108, is a roller 25 109 the inner portion of which projects within the path of travel of the rounded outer ends of the plungers 48 when the same are in their normal retracted position. As these plungers are swung into engagement 30 with the roller 109 they are successively forced inwardly to a position indicated in Fig. 5 of the drawings. After passing a point opposite this roller the collar 53 is engaged by the flanges 110 of an abutment 35 111 held in position upon the standard as by means of adjustable rods 112 and 113. This abutment is curved about the shaft 30 as a center and comprises a member of substantially U-shaped cross section, the two flanges 40 thereof being adapted to engage the collar, whereas the curved connecting portion permits the rounded end of the plunger to pass freely. In this manner the plunger is maintained in its innermost position under a 45 flexible pressure exerted through the spring 57 shown in Fig. 7 of the drawings. Upon passing the lower end of the abutment the collar is freed and the entire plunger and associated parts retracted by means of the 50 heavy coiled spring 54.

Adjustably mounted upon the frame of the machine, as by means of the slotted links 114 and bolts 115 the former being connected by a cross rod 116, is a chute 117 55 comprising upper and lower members 118 and 119 and side members 120 held in fixed relation thereto as by means of tie rods 121. The member 119 projects upwardly to form what may be termed a "stripper arm" 122, this part being positioned between the opposing cradles 43 and being adapted positively to remove the cans from these members as the same are swung into their lowermost position, reference being had to Fig. 6 60 of the drawings.

In order to align the members 59 in their retracted positions, there is formed within the guiding member 43 a recess 123 having therein a spring 124 normally tending to hold a ball 125 within a corresponding recess in the sleeve 59. This device, while permitting a substantially free movement of the sleeve, nevertheless, by forcing the ball within the recess therein, tends to hold the same exactly in the desired position when retracted, as is most clearly shown in Fig. 7 70 of the drawings. A similar device is provided for exactly positioning the sliding jaw 67, the recess 126 formed within the jaw having therein spring 127 and ball 128 75 adapted to co-act with a recess 129 in the guide 66. The outward movement of the jaw is limited by means of a screw 130, the inner end of which co-acts with a slot 131 80 formed in the guide 66. The movement of said jaw when the same is moved laterally inwardly is limited by abutments 132 formed within the upper side of the member 43, as best indicated in Fig. 8 of the drawing.

The operation of the above described embodiment of my invention is substantially as follows: The several can bodies are positioned within the central channel 12 of the supply chute 7, and the corresponding heads occupy positions in the side channels 10, as 85 above described. Assuming the machine to be in rotation, driven as above described, the can receiving members or cradles pass the lower end of the chute and each receives therefrom a can body with the two corresponding heads positioned opposite thereto. Immediately after receiving these parts the sleeve 59 is thrown inwardly by means of the rollers 65 co-acting with the curved portions 78 of the guides 73 and the jaw 67 is 90 then depressed upon the can by means of the flanges 86 upon guides 82. The smooth upper surfaces of the jaws then pass beneath the spring-pressed rollers 101 and are firmly held downwardly upon the can bodies 95 while the plungers 48 are forced inwardly by rollers 109 as above described, this movement driving the heads upon the body of the can. The plungers are thereupon flexibly held in their innermost position by means 100 of the abutments 111, being thus prevented from rattling or straying while the jaws 67 are raised by the flanges 87 and the sleeve 59 retracted by the curved portions 79 of guides 73. This flexible pressure is brought to 105 bear upon the can heads by virtue of a slight movement of collar 53 relative to the plunger 50 caused by the engagement of this member with the abutment 111. Collar 53 being pressed inwardly moves the pin 51 within the slot 52 and through spring 57 110 exerts the desired pressure. The can is thus not only prevented from rattling or straying, but the effect of slight inequalities in length is readily compensated for. The 115 120 125 130

headed can then comes into contact with the rigid stripper arm 122 and, being held in position merely by the flexible pressure exerted through spring 57 as above described, is readily drawn from the cradle and discharged into the chute 117. This cycle of operations is repeated for each can body and, as the can receiving members may be positioned closely together owing to the peculiar movement of the jaw 67, a high rate of production of the machine is attained with a relatively low peripheral speed, the production in machines of this class often being limited by the peripheral speed of the rotating parts inasmuch as it is necessary with a gravity feed, that the bodies drop into the can receiving member.

It will thus be seen that I have provided a machine eminently adapted to accomplish the objects of this invention and possessing advantages many of which will be apparent from the above description and many of which can be appreciated only by the actual use of the same. The several parts are, as above pointed out, readily adjustable to accommodate articles of different sizes and the operation of the machine is almost entirely without jar, the engagement of the moving parts with the fixed members with which they contact being cushioned as by means of the rounded corners upon the upper ends of jaws 67 and upon the outer surface of the collars 53. The pivotally mounted chute, moreover, is a feature of considerable value, inasmuch as it renders all parts of the machine readily accessible, and the positive stripper arm is far more satisfactory in action than the unreliable ejecting means which have been in somewhat general use.

The feature of my invention, moreover, whereby the heading action is accomplished by an unyielding and forceful movement and yet the headed can is thereafter maintained in the desired position by a flexible and readily adjustable pressure upon the heads thereof, is of marked importance. The flexible pressure upon the jaws at the moment of heading is also of material value as any desired pressure may thus be applied independent of wear of parts or variation in the size of the can. It will also be noted that I have provided means whereby the entire series of receiving members upon one side of the machine may be adjusted without changing their relative positions with reference one to another. In this manner the can receiving members upon the two sides of the machine may be adjusted so as to be in proper alinement with a minimum of effort and waste of time.

It may be noted that the term "can receiving" is used throughout this specification and in the following claims in a broad sense as descriptive of any part or parts adapted to receive a can or similar article.

It may also here be noted that the expression "operative portion" as used throughout the following claims with reference to can receiving means denotes that part within which the can is to be positioned.

As many changes could be made in the above construction and many apparently widely different embodiments of my invention could be made without departing from the scope thereof, I intend that all matter contained in the above description or shown in the accompanying drawings shall be interpreted as illustrative and not in a limiting sense.

I claim—

1. In can forming machinery, a supply chute pivotally mounted upon the frame of a machine and movable into and out of operative relation therewith adapted to guide cans thereto, and means upon said machine adapted to limit the movement of said chute.

2. In can forming machinery, a supply chute pivotally mounted upon the frame of a machine adapted to guide can heads and can bodies thereto.

3. In can forming machinery, a pivotally mounted chute comprising separate guiding channels for the heads and the bodies of the cans.

4. In can forming machinery, in combination, a pivotally mounted chute comprising separate guiding channels for the heads and the bodies of the cans, and means upon said chute adapted to be moved into the path of travel of said bodies and heads to prevent the passage thereof.

5. In can forming machinery, in combination, a pivotally mounted chute for guiding cans to a machine, and means upon said chute adapted to be moved into the path of travel of said cans to prevent the passage thereof.

6. In can forming machinery, in combination, a pivotally mounted chute comprising separate guiding channels for the heads and bodies of the cans, and means mounted upon said chute adapted to be moved into the path of travel of said bodies comprising a pivotally mounted arm and spring-pressed means adapted to retain said arm in each of two alternative positions.

7. In can forming machinery, a chute pivotally mounted upon the frame of a machine adapted to guide cans thereto, and means upon said machine adapted to limit the movement of said chute, said chute comprising two portions, one of the same being inclined with respect to the other and said pivot being adjacent the junction of said portions.

8. In can forming machinery, a chute pivotally mounted upon the machine, and means upon the machine adapted to limit the movement of said chute, said chute comprising separate guiding channels for the heads of

the cans, and a guiding channel for the bodies thereof positioned intermediate said first-mentioned channels.

9. In can forming machinery, in combination, a supply chute pivotally mounted upon the frame of the machine, said chute comprising separate channels for the heads of the cans and an intermediate channel for the bodies thereof, and means positioned 10 upon said chute adapted to be swung into the paths of travel of said bodies and said heads and to prevent the passage thereof.

10. In can forming machinery, in combination, a pair of arms rigidly mounted upon 15 the machine, a cross bar connecting said arms, a supply chute pivotally mounted upon said cross bar, means upon said machine adapted to hold said chute in operative position, said chute comprising separate 20 channels for the heads of the cans and a channel positioned between said first-mentioned channels for the bodies thereof, and means mounted upon said chute adapted to be moved into the paths of travel of said 25 heads and bodies and prevent the passage thereof.

11. In a machine of the class described, in combination, a shaft, and a plurality of can receiving members mounted upon said shaft, 30 said members being in fixed relation one to another and angularly adjustable relative to said shaft.

12. In a machine of the class described, in combination, a shaft, a plurality of can receiving members upon said shaft, and means 35 adapted to adjust said members simultaneously and in equal degree with reference to said shaft.

13. In a machine of the class described, in combination, a shaft, a rigid member adjustably mounted upon said shaft, and a plurality of can receiving members mounted 40 upon said rigid member.

14. In a machine of the class described, in combination, a shaft, a pair of rigid members adjustably mounted upon said shaft, and a series of can receiving members mounted 45 upon each of said rigid members, the can receiving members upon one of said shafts being positioned substantially opposite the corresponding can receiving members upon the other of said rigid members.

15. In a machine of the class described, in combination, a shaft, and two series of can receiving members mounted upon said shaft, said can receiving members in each series being in fixed relation one to another and each series of can receiving members being 50 adjustable relative to the other.

60 16. In a machine of the class described, in combination, a shaft, a pair of rigid members mounted upon said shaft, said rigid members being adjustable with relation to 65 said shaft, means holding said rigid members in fixed relation one to another, and

can receiving means upon each of said rigid members.

17. In a machine of the class described, in combination, a shaft, a pair of rigid members adjustably mounted upon said shaft, 70 rigid means connecting said rigid members and adapted to hold the same in fixed relation one to another, and a series of can receiving members detachably mounted upon each of said first-mentioned rigid members, 75 the can receiving members upon each of said rigid members being substantially in alinement with the corresponding members upon the other thereof.

18. In a machine of the class described, in combination, a shaft, a pair of rigid disks adjustably mounted upon said shaft, each disk being provided with an opening, the axis of which is substantially parallel to said shaft, a rigid member fitting said openings 80 and holding said disks in fixed relation one to another, and a series of can receiving members bolted about the circumference of said disks, the can receiving members upon one of said disks being substantially in alinement 85 with the corresponding members upon the other thereof.

19. In a machine of the class described, in combination, a can-receiving member, a member mounted adjacent thereto, means 90 adapted to move said second-mentioned member opposite the operative portion of said can-receiving member, guiding means adapted to permit movement of said second member in a plane transverse to the plane of travel of said can-receiving member, and means adapted to move the said member toward said can-receiving member.

20. In a machine of the class described, in combination, a can-receiving member, a member mounted adjacent thereto, means 100 adapted to move said second-mentioned member opposite the operative portion of said can-receiving member, guiding means adapted to permit movement of said second member in a plane transverse to the plane of travel of said can-receiving member, and independent means adapted to move the same 110 toward said can-receiving member.

21. In a machine of the class described, in combination, a can-receiving member, a member mounted adjacent thereto, and means adapted to move said second-mentioned member in two directions into a position opposite the operative portion of and closely adjacent said can-receiving member 115 one of said directions being substantially normal to the direction of travel of said can-receiving member.

22. In a machine of the class described, in combination, a can-receiving member, a member mounted adjacent thereto, and means adapted to move said second-mentioned member in two directions into a position opposite the operative portion of and 120

5 closely adjacent said can-receiving member, said two directions being substantially at right angles one with another and one of said directions being substantially normal to the direction of travel of said can-receiving member.

23. In a machine of the class described, in combination, a shaft, a can-receiving member mounted thereon, a member mounted adjacent said can-receiving member, and means adapted to move said second-mentioned member in a direction parallel to said shaft to a position substantially opposite the operative portion of said can-receiving member.

10 24. In a machine of the class described, in combination, a can-receiving member, a member mounted adjacent thereto, and means adapted to move said second-mentioned member in two directions into a position opposite the operative portion of and closely adjacent said receiving member, said movement in each direction being substantially rectilinear.

15 25. In a machine of the class described, in combination, a can-receiving member, a member mounted adjacent thereto, means adapted to slide said second-mentioned member opposite said can-receiving member and toward the same and means adapted to insure a substantially rectilinear direction of said last movement.

20 26. In a machine of the class described, in combination, a movable can-receiving member, a member mounted adjacent thereto, and means adapted to slide said second-mentioned member in a plane substantially at right angles to the direction of movement of said movable member, into a position opposite the operative portion thereof and closely adjacent the same.

25 27. In a machine of the class described, in combination, a movable can-receiving member mounted adjacent thereto, and relatively stationary means adapted to slide said second-mentioned member toward said can-receiving member.

30 28. In a machine of the class described, in combination, a shaft, a can-receiving member mounted thereon, relatively stationary means adapted to slide said member into a position opposite the operative position of said can-receiving member, and independent relatively stationary means adapted to slide said member toward said can-receiving member.

35 29. In a machine of the class described, in combination, a shaft, a plurality of can-receiving members, mounted thereon, a member mounted adjacent each of said can-receiving members, relatively stationary members adapted successively to slide said members into positions the operative portions of the corresponding can-receiving members, and independent relatively stationary means

adapted successively to slide said members toward the corresponding can-receiving members.

30. In a machine of the class described, in combination, means adapted to receive a can body and head and separate means adapted to apply pressures of different intensities to said head in a direction substantially parallel to the axis of the can.

10 31. In a machine of the class described, in combination, means adapted to receive a can body and head, means adapted to apply a pressure of a certain intensity to said head in a direction substantially parallel to the axis of the can, and independent means adapted to apply to the same parts and in the same direction a pressure of a different intensity.

15 32. In a machine of the class described, in combination, means adapted to receive a can body and head, rigid means adapted to apply pressure to said head in a direction substantially parallel to the axis of the can, and flexible means adapted to apply pressure to the same part and in the same direction.

20 33. In a machine of the class described, in combination, means adapted to receive a can body and head, rigid means adapted to apply a pressure to said head in a direction substantially parallel to the axis of the can, and flexible means adapted to apply pressure to the same parts and in the same direction, each of said rigid means and said flexible means being adjustable.

25 34. In a machine of the class described, in combination, means adapted to receive a can body and head, means adapted to engage said head, rigid means adapted to move said last-mentioned means toward said head, and means adapted flexibly to hold said second-mentioned means in the position into which it is moved.

30 35. In a machine of the class described, in combination, means adapted to receive a can body and head, means adapted to engage said head, rigid means adapted to move said last-mentioned means toward said head, and means adapted flexibly to hold said second-mentioned means in the position to which it is moved, each of said two last-mentioned means being adjustable.

35 36. In a machine of the class described, in combination, means adapted to receive a can body and head, a member adapted to engage said head, means adapted to engage said member and move the same rigidly toward said head, and means adapted flexibly to hold the same in the position to which it is moved.

40 37. In a machine of the class described, in combination, means adapted to receive a can body and heads, means adapted simultaneously to engage each of said heads rigid means adapted to move each of said last-mentioned means toward the corresponding head, and means adapted flexibly to hold

- each of the same in the position to which it is moved.
38. In a machine of the class described, in combination, means adapted to receive a can body and head, a member adapted to engage said head, a spring, rigid means adapted to apply pressure directly to said member, and rigid means adapted to apply pressure to said member through said spring.
39. In a machine of the class described, in combination, movable means adapted to receive a can body and head, a member movable with relation to said means adapted to engage said head, fixed means adapted directly to contact said member, a spring, and fixed means adapted to press said member through said spring.
40. In a machine of the class described, in combination, means adapted to receive a can body and heads, a relatively movable member opposite each of said heads adapted to engage the same, fixed means adapted to contact said members directly, springs, and fixed means adapted to press said members through said springs.
41. In a machine of the class described, in combination, a shaft, means mounted upon said shaft adapted to receive a can body and heads, a relatively movable member adapted to engage each of said heads, fixed means adapted directly to engage said members, a spring corresponding to each of said members, and independent fixed means adapted to press each of said members through the corresponding spring.
42. In a machine of the class described, in combination, a shaft, means mounted upon said shaft adapted to receive a can body and heads, a relatively movable spring-retracted plunger mounted adjacent each end of said means and adapted to engage the corresponding head, a rigid member projecting within the path of travel of each of said plungers adapted to force the same toward the corresponding heads, springs, and rigid means adapted to press each of said plungers toward the corresponding head, said pressure being applied through said springs.
43. In a machine of the class described, in combination, a shaft, means mounted upon said shaft adapted to receive a can body and heads, a relatively movable spring-retracted plunger mounted adjacent each end of said means and adapted to engage the corresponding heads, a rigid member projecting within the path of travel of each of said plungers adapted to force the same toward the corresponding head, springs, and rigid means adapted to press each of said plungers toward the corresponding head, said pressure being applied through said springs and both of said fixed means being adjustable relative to said plunger.
44. In a machine of the class described, in combination, a shaft, means mounted upon said shaft adapted to receive a can body and heads, a relatively movable spring-retracted plunger mounted adjacent each end of said means and adapted to engage the corresponding heads, a rigid member projecting within the path of travel of each of said plungers adapted to force the same toward the corresponding head, a collar mounted upon each of said plungers, a spring interposed between said collar and said plunger, and fixed means positioned out of the path of travel of said plungers and within the path of travel of said collars adapted to apply pressure to said plungers through said collars and said springs.
45. In a machine of the class described, in combination, a can-receiving member, a member mounted adjacent thereto, means adapted to move said second-mentioned member opposite said can-receiving member, means adapted to move the same toward said can-receiving member, a member mounted adjacent said can-receiving member and movable in a direction substantially parallel to the axis of the can, and independent means adapted to force the said last-mentioned member toward said can with pressures of different intensities.
46. In a machine of the class described, in combination, movable means adapted to receive a can body and heads, a member mounted adjacent thereto, means adapted to move said member toward said means in a plane substantially at right angles to the direction of movement thereof, means adapted to engage a head upon said can, rigid means adapted to move said last-mentioned means toward said head, and means adapted flexibly to hold the same in the position into which it is moved.
47. In a machine of the class described, in combination, movable means adapted to receive a can body and head, a member mounted adjacent thereto, means adapted to move said member toward said first-mentioned means, said movement being in a plane substantially at right angles to the direction of movement of said first-mentioned means, means adapted to engage said head, rigid means adapted to move said last-mentioned means toward said head, and means adapted flexibly to hold the same in the position into which it is moved, said several means being adapted to cause said last-mentioned action to take place subsequent to that first-described.
48. In a machine of the class described, in combination, a shaft, means adapted to receive a can body and head mounted upon said shaft, a member mounted adjacent said first-mentioned means, means adapted to move said member in a direction parallel to said shaft, means adapted to move the same in a direction toward said first-mentioned means, a second member mounted ad-

5 jacent said first-mentioned means and adapted to engage said head, rigid means adapted to move said member toward the head, and means adapted flexibly to hold the same in the position into which it is moved, said parts being adapted to cause the above steps to take place in the order stated.

49. In a machine of the class described, in combination, a shaft, means mounted thereon adapted to receive a can body and a head, a relatively movable member mounted adjacent said shaft, stationary means adapted to force said member into a position opposite the operative position of said first-mentioned means and thence downwardly toward said first-mentioned means, a plunger mounted opposite one end of said first-mentioned means, a rigid member interposed in the path of travel of said plunger adapted to engage the same and force it toward said head, and means adapted flexibly to hold said plunger in the position into which it is forced, said means being adapted to cause said movement of said plunger to take place subsequent to said movements of said first-mentioned member.

50. In a machine of the class described, in combination, a shaft, means mounted thereon adapted to receive a can body and head, a relatively movable member mounted adjacent thereto, fixed means adapted to move said member into a position opposite and closely adjacent the operative position of said first-mentioned means, said member being adapted to move in a plane parallel to said shaft, a relatively movable spring-retracted plunger mounted adjacent one end of said can-receiving means, and rigid means projecting within the path of travel of said plunger adapted to engage the same and move the same toward the said head, a collar flexibly mounted upon said plunger, and means without the path of travel of said plunger and within the path of travel of said collar adapted to engage said collar and flexibly to hold said plunger in the position into which it is moved.

51. In a machine of the class described, in combination, a shaft, means mounted thereon adapted to receive a can body and head, a relatively movable member mounted adjacent thereto, fixed means adapted to move said member into a position opposite and closely adjacent the operative portion of said first-mentioned means, said member being adapted to move in a plane parallel to said shaft, a relatively movable spring-retracted plunger mounted adjacent one end of said can receiving means, rigid means projecting within the path of travel of said plunger adapted to engage the same and move the same toward the said head, a collar flexibly mounted upon said plunger, and means without the path of travel of said plunger and within the path of travel of said collar

adapted to engage said collar and flexibly to hold said plunger in the position into which it is moved, said several fixed members being adjustable with relation to the parts upon which they are mounted.

70

52. In a machine of the class described, in combination, a movable member adapted to receive a can-body, a member adapted to close over a can body positioned therein, means adapted to close said second member, and independent means adapted to press said second mentioned member toward said first mentioned member.

75

53. In a machine of the class described, in combination, a member adapted to receive a can body, a member adapted to close over a can body positioned therein and a spring pressed member adapted to apply pressure directly to said second mentioned member.

80

54. In a machine of the class described, in combination, a member adapted to receive a can body, a member adapted to close over a can body positioned therein, and relatively stationary means adapted flexibly to press said second mentioned member toward said first mentioned member.

85

55. In a machine of the class described, in combination, means adapted to receive a can body, a member adapted to close over a can body positioned therein and a spring-pressed pivotally mounted arm positioned within the plane of said second mentioned member in closed condition and adapted to apply pressure thereto.

90

56. In a machine of the class described, in combination, a member adapted to receive a can body, a member adapted to close over a can body positioned therein, a spring pressed pivotally mounted arm adapted to press said second mentioned member toward the first mentioned member, and adjustable stops adapted to limit the movement of said arm.

100

57. In a machine of the class described, in combination, a member adapted to receive a can-body a member adapted to close over a can body positioned therein, a spring-pressed pivotally mounted arm adapted to press said second mentioned member toward the first mentioned member, and adjustable stops adapted to limit the movement of said arm, said arm being positioned within the plane of said second mentioned member in closed condition.

110

58. In a machine of the class described, in combination, means adapted to receive a can body, a member adapted to close over a can body positioned therein, a spring-pressed arm mounted adjacent said second mentioned member and having parts thereon projecting in the path of travel thereof and adjustable stops to limit the movement of said arm, said arm being adapted to apply pressure to said second mentioned member.

115

59. In a machine of the class described, in combination, a movable member adapted to

120

125

130

receive a can body, a member adapted to close over a can body positioned therein, a lever mounted adjacent the path of travel of said first mentioned member, a spring-
5 pressed member adapted to contact said lever, adjustable stops adapted to limit the movement of said lever and a roller upon said lever adapted to contact and apply pressure directly to said second mentioned member.

60. In a machine of the class described, in combination, a movable member adapted to receive a can body and relatively fixed means positioned adjacent the path of travel of said movable member and adapted to engage and withdraw a can positioned therein, said fixed means being adjustable with reference to the parts upon which it is positioned.

61. In a machine of the class described, in combination, a movable member adapted to receive a can and a relatively stationary adjustably mounted member positioned adjacent the path of travel in said movable member and within the path of travel of a can positioned therein and adapted to engage and withdraw said can.

62. In a machine of the class described, in combination, a movable member adapted to receive a can, a relatively stationary adjustably mounted member positioned adjacent the path of travel of said movable member and adapted to engage and withdraw a can positioned therein and a receiving chute operatively positioned with respect to said relatively stationary member and adapted to receive cans therefrom.

63. In a machine of the class described, in combination a pair of movable can receiving members and a relatively stationary curved member adjustably positioned between the paths of travel of said first mentioned members and adapted to engage and withdraw a can positioned therein.

64. In a machine of the class described, in combination, a shaft, a pair of substantially aligned can receiving members mounted upon said shaft, a receiving chute and a member fixed upon said receiving chute extending between the paths of travel of said can receiving members as the same are rotated by said shaft and adapted to engage and withdraw a can positioned therein, said receiving chute being adjustable with reference to the parts upon which it is mounted.

65. In a machine of the class described, in combination, a shaft, a plurality of can receiving members mounted upon same, said members being in fixed relation one to another and adjustable relative to said shaft and a pivotally mounted chute adapted to supply cans to said can receiving members.

66. In a machine of the class described, in combination, a shaft, a plurality of series of can receiving members mounted upon said shaft, means adapted to adjust the members

of each series simultaneously and in equal degree with reference to said shaft, a supply chute pivoted upon said machine, adapted to supply cans to said can receiving members and means on said machine adapted to limit the movement of said supply chute.

67. In a machine of the class described, in combination, a shaft, a pair of members adjustably mounted upon said shaft, a series of can receiving members rigidly mounted on each of said adjustable members and a supply chute comprising separate guiding channels for the heads and bodies of the cans, parts on said chute being adapted to pass through corresponding slots in said can receiving members.

68. In a machine of the class described, in combination, a shaft, a plurality of can receiving members mounted upon the same, said members being in fixed relation one to another and adjustable relative to said shaft, a member mounted adjacent each of said can receiving members, means adapted to move said last mentioned members opposite the operative portion of the corresponding can receiving members and means adapted to move the same toward said can receiving members.

69. In a machine of the class described, in combination a shaft, a plurality of can receiving members mounted upon said shaft, said members being in fixed relation one to another and adjustable relative to said shaft, a member mounted adjacent each of said can receiving members and means adapted to slide each of said last mentioned members toward the operative portions of said can receiving members.

70. In a machine of the class described, in combination, a shaft, a plurality of can receiving members mounted upon said shaft, means adapted to adjust said members simultaneously and in equal degree with reference to said shaft, a member mounted adjacent each of said can receiving members and means adapted to move each of said last mentioned members in a direction parallel to said shaft and thence in a direction radial with respect to said shaft and toward the operative portions of said can receiving members.

71. In a machine of the class described, in combination, a shaft, a pair of members adjustably positioned upon said shaft, a can receiving member upon each of the same, a member connecting said pair of members adapted to hold the can receiving member upon each of the same substantially in alignment with the other thereof, and separate means adapted to apply pressures of different intensities to the heads of a can positioned therein in a direction substantially parallel to the axis thereof.

72. In a machine of the class described, in combination, a shaft, a pair of members ad-

justably mounted upon said shaft, rigid means interconnecting said pair of members, a member mounted upon each of said first mentioned members adapted to receive a can body and head, means adapted to engage said heads, rigid means adapted to move said last mentioned means toward said heads, and means adapted flexibly to hold said means in the position to which they are

10 moved.

73. In a machine of the class described, in combination, a shaft, a pair of members adjustably mounted on said shaft, a member positioned upon each said first mentioned 15 members and adapted to receive a can body and head, a member mounted adjacent each of said can receiving members, means adapted to move said last mentioned members substantially parallel to said shaft and 20 thence in a direction substantially radial with respect to said shaft toward the operative portions of the corresponding can receiving members, means adapted to engage heads positioned in said can receiving members, rigid means adapted to move said last 25 mentioned means toward the corresponding heads, and means adapted flexibly to hold said means in the position into which they are moved.

74. In a machine of the class described, in combination, a shaft, a pair of rigid members mounted upon said shaft, can receiving means upon each of said members, a member connecting said first mentioned members 35 adapted to hold said can receiving means in alinement, a member mounted adjacent each of said can receiving means, means adapted rigidly to move said last mentioned members toward a can positioned in the corresponding can receiving means, and means adapted flexibly to hold said members in the positions into which they are moved.

75. In a machine of the class described, in combination, a shaft, a pair of rigid members adjustably mounted upon said shaft, can receiving members upon each of said rigid members, means connecting said rigid members adapted to hold the can receiving members upon each of the same in alinement 45 with the corresponding parts upon the other thereof, a member mounted adjacent each of said can receiving members, means adapted to slide each of the same toward the corresponding can receiving member, means 50 mounted adjacent each of said can receiving members, rigid means adapted to move said last mentioned means toward a can positioned in the corresponding can receiving member, and means adapted flexibly to hold 55 said means in the position into which it is moved.

76. In a machine of the class described, in combination, a movable can receiving member, a member mounted adjacent thereto;

means adapted to move said second mentioned member opposite the operative portion of said can receiving member, means adapted to force the same toward said can receiving member, and a relatively stationary member positioned adjacent to the path 70 of travel of said movable member and adapted to engage and withdraw a can positioned therein.

77. In a machine of the class described, in combination, a shaft, a pair of rigid members mounted thereon, a pair of substantially alined can receiving members mounted respectively one upon each of said rigid members, a relatively movable member mounted adjacent each of said can receiving members, 80 means adapted to move said last mentioned members within a plane taken through said shaft toward the corresponding can receiving members, and relatively stationary means positioned between the paths of travel 85 of said can receiving members and adapted to engage and withdraw a can positioned therein.

78. In a machine of the class described, in combination, movable means adapted to receive a can body and head, means adapted to engage said head, rigid means adapted to move said last mentioned means toward said head, means adapted flexibly to hold said means in the position into which it is 90 moved, a relatively stationary member positioned adjacent the path of travel of said movable means and adapted to engage and withdraw the said can positioned therein.

79. In a machine of the class described, in combination, a shaft, a pair of rigid members mounted thereon, a can receiving member upon each of said rigid members, said can receiving members being substantially 100 in alinement one with another, means 105 mounted adjacent each of said can receiving members and movable with relation thereto, means adapted to move said last mentioned means toward a can positioned in the corresponding can receiving member, means 110 adapted flexibly to hold said means in the position into which it is moved, and a relatively stationary member mounted between the paths of travel of said can receiving members and adapted to engage and withdraw a can positioned therein.

80. In a machine of the class described, in combination, a shaft, a pair of rigid members mounted upon said shaft, means upon each of said rigid members adapted to receive a can body and head, means mounted adjacent each of said can receiving means adapted to engage a head positioned therein, rigid means adapted to move said last mentioned means toward the corresponding 125 heads, means adapted flexibly to hold said means in the position into which they are moved, a movable member mounted adjacent

- each of said can receiving means, means adapted to move said movable member toward the corresponding can receiving means within a plane including said shaft, and a 5 relatively stationary member mounted between the paths of travel of said can receiving means adapted to engage and withdraw a can positioned therein.
81. In a machine of the class described, in 10 combination, a shaft, a pair of rigid members mounted upon said shaft, means upon each of said rigid members adapted to receive a can body and head, a member mounted adjacent each of said can receiving means, 15 means adapted to move said members toward the corresponding can receiving means within a plane including said shaft, means adjacent each of said can receiving means adapted to engage a head therein, rigid 20 means adapted to move said last mentioned means toward said head, means adapted flexibly to hold said means in the position into which it is moved, and relatively stationary can-engaging means mounted between the 25 paths of travel of said can receiving means, said several means being adapted to operate upon parts positioned within said can receiving means in the order described.
82. In a machine of the class described, in 30 combination, movable can receiving means, a member mounted adjacent thereto, means adapted to move said member toward the operative portion of said can receiving means, means adapted to move said member 35 away from the operative portion of said can receiving means, and means adapted flexibly to press said member toward said can receiving means, said last mentioned means being adapted to become operative 40 subsequent to the action of said first mentioned means, and previous to the action of said second mentioned means.
83. In a machine of the class described, in 45 combination, means adapted to receive a can body, a member mounted adjacent thereto, means adapted to force said member toward the operative portion of said can receiving means and release the same, means adapted flexibly to press said member toward said 50 can receiving means subsequent to its release by said first mentioned forcing means, and means adapted positively to withdraw said member from the operative portion of said can receiving means.
84. In a machine of the class described, in 55 combination, means adapted to receive a can body and head, a member mounted adjacent thereto, means adapted to force said member toward a head positioned in said first 60 mentioned means, means adapted flexibly to hold said member in the position into which it is moved, a second member mounted adjacent said can receiving means and movable with relation thereto, and means adapt- 65 ed flexibly to press said second member toward the operative portion of said can receiving means simultaneously with the movement of said first-mentioned member.
85. In a machine of the class described, in 70 combination, means adapted to receive a can body, a movable jaw adapted to close upon a can body positioned in said can receiving means, and spring-pressed means adapted to tend to maintain said jaw, in retracted condition, in a predetermined position.
86. In a machine of the class described, in 75 combination, means adapted to receive a can body, a slideable jaw adapted to close over a can body positioned within said receiving means, and a spring-pressed member adapted to tend to hold said jaw, when retracted, in a predetermined position.
87. In a machine of the class described, in 80 combination, means adapted to receive a can body, means adapted to clamp a can body within said receiving means, and a plurality of spring-pressed means adapted normally to tend to maintain the corresponding parts of said clamping means in a predetermined position.
88. In a machine of the class described, in 85 combination, a slideable member, a member against which said first-mentioned member slides, and a spring-pressed member between said first-mentioned members adapted to tend to hold the same in a predetermined relative position.
89. In a machine of the class described, in 90 combination, can heading means comprising means adapted to engage the heads of a can, and a discharge chute comprising a member adapted to engage a side of a can between said head engaging means, whereby said head engaging means form in function a portion of the discharge chute.
90. In a machine of the class described, in 95 combination, movable can heading means comprising means adapted to engage the heads of a can, and a relatively stationary discharge chute comprising a member adapted to engage a side of a can between said head engaging means, whereby said head engaging means form in function a portion of the discharge chute.
91. In a machine of the class described, in 100 combination, movable can heading means comprising means adapted to engage the heads of a can, and a relatively stationary discharge chute comprising a pair of members adapted to engage opposite sides of a 105 can between said head engaging means, whereby said engaging means form in function a portion of the discharge chute.
92. In a machine of the class described, in 110 combination, can heading means comprising rotatably mounted can receiving members provided with slots extending substantially in their plane of rotation, and a supply 115

chute for said can heading means having a portion resting within said slots.

93. In a machine of the class described, in combination, can heading means, and a supply chute leading thereto comprising independent channels for the bodies and each of the heads of the cans, said channels being adjustably connected by tie-rods.

94. In a machine of the class described, in combination, a shaft having two members mounted thereon, a plurality of spaced can receiving members mounted upon each of said first-mentioned members, a supply chute discharging within said can receiving members, a discharge chute adapted to draw said cans from said can receiving members, clamping means for each of said can receiving members comprising a jaw adapted to move first longitudinally and then radially with respect to said shaft, and means adapted to impart said movements to said jaws.

95. In a machine of the class described, in combination, a shaft having two members mounted thereon, a plurality of spaced can receiving members mounted upon each of said first-mentioned members, a supply chute discharging within said can receiving members, a discharge chute adapted to draw said cans from said can receiving members, clamping means for each of said can receiving members comprising a jaw adapted to move first longitudinally and then radially with respect to said shaft, and means adapted to impart said movements to said jaws, said first-mentioned members being angularly adjustable with respect to said shaft.

96. In a machine of the class described, in combination, a shaft having two members mounted thereon, a plurality of spaced can receiving members mounted upon each of said first-mentioned members, a supply chute discharging within said can receiving members, a discharge chute adapted to draw said cans from said can receiving members, clamping means for each of said can receiving members comprising a jaw adapted to move first longitudinally and then radially with respect to said shaft, means adapted to impart said movements to said jaws, and means adapted to exert an additional pressure upon said jaws during a portion of their rotation about the axis of said shaft.

97. In a machine of the class described, in combination, a shaft having two members mounted thereon, a plurality of spaced can receiving members mounted upon each of said first-mentioned members, a supply chute discharging within said can receiving members, a discharge chute adapted to draw said cans from said can receiving members, clamping means for each of said can receiving members comprising a jaw adapted to move first longitudinally and then radially with respect to said shaft, means

adapted to impart said movements to said jaws, means adapted to exert an additional pressure upon said jaws during a portion of their rotation about the axis of said shaft, plungers adapted to force heads upon can bodies within said can receiving members, and means adapted to actuate said plungers during the subjection of said jaws to said additional pressure.

98. In a machine of the class described, the combination of a fixed socket portion adapted to receive the body and head of a can, a movable clamping portion having a straight line forward and back movement in a line substantially parallel with the axis of a can and having a straight line clamping movement at substantially right angles to the axis of a can and adapted to coöperate with the fixed socket portion to surround and clamp the body and head of a can, and means for driving the can head into place after the clamping operation, substantially as described.

99. In a machine of the class described, the combination of a fixed socket portion adapted to receive the body and head of a can, a movable clamping portion having a straight line forward and back movement in a line substantially parallel with the axis of a can and having a straight line clamping movement at substantially right angles to the axis of a can and adapted to coöperate with the fixed socket portion to surround and clamp the body and head of a can, and a plunger adapted to drive the head of the can into place after the clamping operation, substantially as described.

100. In a machine of the class described, the combination of a fixed socket portion adapted to receive the body and head of a can, a movable clamping portion having a straight line forward and back movement in a line substantially parallel with the axis of a can and having a straight line clamping movement at substantially right angles to the axis of a can and adapted to coöperate with the fixed socket portion to surround and clamp the body and head of a can, a plunger adapted to drive the head of the can into place after the clamping operation, a cam for actuating the movable clamping mechanism, and a cam for thereafter actuating the plunger, substantially as described.

101. In a machine of the class described, the combination of a fixed socket portion adapted to receive the body and head of a can, a movable clamping portion having a straight line forward and back movement in a line substantially parallel with the axis of a can and having a straight line clamping movement at substantially right angles to the axis of a can, and adapted to coöperate with a fixed socket portion to surround and clamp the body and head of a can, a plunger

adapted to drive the head of the can into place after the clamping operation, a rotatable carrier upon which the clamping mechanism is mounted, a fixed cam adapted to 5 actuate the clamping mechanism during the rotation thereof, and a fixed cam adapted to similarly actuate the plunger after the clamping operation, substantially as described.

10. 102. In a machine of the class described, the combination of two carrier plates, companion clamping mechanism on each of the carrier plates adapted to apply heads on opposite ends of the same can body, each 15 clamping mechanism comprising a fixed socket portion adapted to have one end of the can body and head dropped thereinto, a clamping portion having a straight line back and forth movement in a line substantially parallel with the axis of a can, and adapted 20 to be initially retracted to permit the insertion of the can body and head into the socket portion, said clamping portion also having an independent straight line clamping movement at substantially right angles to the axis of a can, a fixed cam adapted to move the clamping portion forward and thereafter impart a clamping movement to such portion, and means for thereafter driving 25 the can head into place, substantially as described.

103. In a machine of the class described, the combination of two carrier plates, companion clamping mechanism on each of the carrier plates adapted to apply heads on opposite ends of the same can body, each 35 clamping mechanism comprising a fixed socket portion adapted to have one end of the can body and head dropped thereinto, a clamping portion having a straight line back and forth movement in a line substantially parallel with the axis of a can and adapted 40 to be initially retracted to permit the insertion of the can body and head into the socket portion, said clamping portion also having an independent straight line clamping movement at substantially right angles to the axis of a can, a fixed cam adapted to move the clamping portion forward and 45 thereafter impart a clamping movement to such portion, a plunger adapted to drive the can head into place, and a cam for actuating the plunger substantially as described.

104. In a machine of the class described, 55 a header mechanism comprising a fixed socket portion having in its face a semi-cylindrical recess, a tubular sleeve rearwardly extending from the socket portion, a plunger head operable within the recessed portion 60 and having a stem slidably mounted within the tubular sleeve, a rider slidably mounted on the sleeve, an arched clamping portion adapted to coöperate with the recessed socket portion, a mounting connected with 65 the rider for said arched clamping portion,

permitting a straight line clamping movement with respect to the recessed socket, means for moving the rider back and forth along the tubular sleeve, and means for imparting a clamping motion to the arched clamping portion, substantially as described. 70

105. In a machine of the class described, a clamping mechanism comprising a recessed socket portion, an arched clamping portion, 75 a guideway for the arched clamping portion adapted to permit a straight line forward and back movement with respect to the recessed socket, and a guideway for the arched clamping portion for giving thereto a 80 straight line clamping movement toward and from the socket portion at right angles to the forward and back movement, substantially as described.

106. In a machine of the class described, 85 the combination of a recessed socket, a clamping arch coöperating therewith, a guideway for the clamping arch permitting a direct up and down clamping movement with respect to the socket, and a guideway, upon which the first mentioned guideway is slidably mounted, for affording a 90 back and forth movement with respect to the recessed socket and at right angles to the clamping movement, substantially as described. 95

107. In a machine of the class described, a clamping mechanism comprising a recessed socket, a clamping arch coöperating therewith, a guideway for the clamping arch permitting a direct up and down clamping movement with respect to the socket, a tubular sleeve rearwardly extending from the socket, a rider with which the first mentioned guideway is connected, said rider being slidably mounted on the sleeve, and means for 100 imparting a forward thrust to the rider and thereafter imparting a clamping movement to the clamping arch, substantially as described. 105

108. In a machine of the class described, in combination, a fixed socket adapted to receive a can body, and a clamping member having a positioning movement in a direction parallel with the axis of the fixed socket and a clamping movement in a direction at right angles thereto. 115

109. In a machine of the class described, in combination, a fixed socket adapted to receive a can body, and a clamping member for the can body having a straight line positioning movement in a direction parallel with the axis of the fixed socket and a clamping movement in a direction at right angles thereto. 120

110. In a machine of the class described, in combination, a fixed socket adapted to receive a can body, and a clamping member having a positioning movement in a direction parallel with the axis of the fixed socket 125

and a straight line clamping movement in a direction at right angles to said axis.

111. In a machine of the class described, in combination, a fixed socket adapted to receive a can body, and a clamping member having a straight line positioning movement in a direction parallel with the axis of said fixed socket and a straight line clamping movement in a direction at right angles thereto.

112. In a machine of the class described, in combination, a fixed socket adapted to receive a can body, and a cam controlled clamping member having positioning movement in a direction parallel with the axis of the fixed socket and a clamping movement in a direction at right angles thereto.

113. In a machine of the class described, in combination, a fixed socket adapted to receive a can body, a member for clamping the can body within said socket having a positioning movement in a direction parallel with the axis of the can body and a clamping movement in a direction normal to said axis, and cam means for effecting both movements of said clamping member.

114. In a machine of the class described, in combination, a fixed socket adapted to receive the body and head of a can, a member coöperating with said socket to surround and clamp said body and head, means for giving said clamping member a straight line positioning movement, and means for giving the same a straight line clamping movement.

115. In a machine of the class described, in combination, a fixed socket adapted to receive the body and head of a can, a movable member adapted to clamp said body and head within said socket, means for moving said member in a straight line opposite said can body and head, and cam means for moving the same into engagement therewith.

116. In a machine of the class described, in combination, a fixed socket adapted to receive the body and head of a can, a movable member adapted to clamp said body and head within said socket, means for moving said member in a straight line opposite said can body and head, and cam means for moving the same in a straight line into engagement therewith.

117. In a machine of the class described, in combination with can heading means, means for holding the body and head of a can during the heading operation, comprising a fixed socket, a movable member having a complementary socket portion, and means for giving said last mentioned member a straight line positioning movement in a direction parallel to the axis of the can body, and a straight line clamping movement in a direction normal thereto.

118. The combination in a machine of the class described, of can body and head clamp-

ing means comprising a fixed socket, and a movable member having a complementary socket portion, cam means for moving said member into clamping position, and independent cam means for moving the same into clamping engagement.

119. In a machine of the class described, in combination, a fixed socket adapted to receive the body and head of a can, a movable socket adapted to coöperate with the fixed socket to surround and clamp said body and head of the can, positively acting means for forcing said sockets into engagement with the aforementioned parts of the can, and resilient means for holding them in such engagement during the heading operation.

120. In a machine of the class described, in combination, a fixed socket portion adapted to receive the body and head of a can, a complementary movable socket portion adapted to coöperate with said fixed socket portion to surround and clamp said body and head of the can, positively acting means for causing said socket portions to coöperate with said aforementioned parts of the can, means for forcing the head upon the can, and resilient means for holding said sockets in clamping position during the operation of the can heading means.

121. In a machine of the class described, in combination, a fixed socket portion adapted to receive the body and head of a can, a complementary movable socket portion adapted to coöperate with said fixed socket portion to surround and clamp said body and head of a can, means for moving said movable portion into registry with said fixed socket portion, and means for moving it in a different direction, whereby it is caused to engage the aforementioned parts of the can.

122. In a machine of the class described, the combination of a fixed socket adapted to receive the body and head of a can, a movable clamping portion having a straight line forward and back movement in a line substantially parallel with the axis of a can and having a straight line clamping movement at substantially right angles to the axis of a can and adapted to coöperate with the fixed socket portion to surround and clamp the body and head of a can, means for driving the can head into place after the clamping operation, and means for holding said movable clamping portion in resilient engagement with the aforementioned parts of a can during the heading operation.

123. In a machine of the class described, the combination of a fixed socket adapted to receive the body and head of a can, a movable clamping portion having a straight line forward and back movement in a line substantially parallel with the axis of a can and having a straight line clamping

movement at substantially right angles to the axis of a can and adapted to coöperate with the fixed socket portion to surround and clamp the body and head of a can, 5 means for driving the can head into place after the clamping operation, and spring actuated means coöoperating with said movable clamping portion for holding the lat-

ter in resilient engagement with the afore-mentioned parts of a can.

In testimony whereof I affix my signature, in the presence of two witnesses.

CHARLES W. GRAHAM.
